CLAIM

The ornamental design for a portable electronic device, as shown and described.

DESCRIPTION

FIG. 1 is a front perspective view of a portable electronic device in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partially enlarged view of encircled portion 8 as illustrated in FIG. 4; and,

(Continued)

FIG. 9 is a partially enlarged view of encircled portion 9 as illustrated in FIG. 6.

1 Claim, 6 Drawing Sheets
